UNITED STATES PATENT OFFICE

MARTIN BURGER, OF MORRIS, ILLINOIS, ASSIGNOR TO SELF LOCKING SCHURMANN COMPANY, A CORPORATION OF ILLINOIS

MACHINE FOR SETTING UP CARTONS

REISSUED

Application filed September 28, 1928. Serial No. 308,963.

There is a type of egg carton that has transverse partitions integral with the body of the carton, these partitions being adapted to be swung into vertical positions and be hooked at their lower ends through slots in the bottom wall; the bottom wall being pushed up in the middle so as to form in effect a longitudinal partition. These cartons are delivered to the user in a collapsed or flattened condition, the bottom wall being flattened out and the transverse partitions lying flat upon the same.

The object of the present invention is to produce a simple and novel machine for setting up a carton of the type described above.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a rear view of a machine embodying the present invention, in its normal open position; Fig. 2 is a plan view of the collapsed carton, on a reduced scale; Fig. 3 is an edge view of the collapsed carton, the thickness of the material of which the carton is made being exaggerated; Fig. 4 is a top plan view of the machine, opened and having thereon a collapsed carton, but only part of the carton being shown; Figs. 5 and 6 are sections taken approximately on line 5-6 of Fig. 4, showing the parts of the machine in two different positions; Figs. 7 and 8 are transverse sections through Figs. 5 and 6 respectively; Fig. 9 is a view similar to Figs. 7 and 8, illustrating the final positions of the parts in the setting up of the carton; Fig. 10 is a section taken on line 10-10 of Fig. 8, showing only a fragment of the machine and carton; and Fig. 11 is a section taken on line 11-11 of Fig. 9 and illustrating the same parts as in Fig. 10.

The carton to be operated upon may be made of a single piece, as shown in the drawings, comprising a bottom section A, two side wall sections B and C, a cover section D and a false top divided into a series of transverse

sections E, each integrally united with or secured to the two side sections at one end, so that it may be swung down into a vertical position when the carton is set up. In the bottom of the carton are transverse slots F through which the hook-shaped lower ends e of the flaps may be pressed so as to be interlocked with the bottom of the carton. Each of the transverse partition elements has two of the hook-shaped portions, one on each side of the longitudinal center of the carton. The bottom wall of the carton is scored along the longitudinal center line, as indicated at a, so that it may be folded along the center line in setting up the carton.

The carton is delivered to the user in the flattened condition illustrated in Figs. 2 and 3. Upon pressing up what are the diagonally opposite long edges of the carton when set up, namely at the points g and h in Fig. 3, the body of the carton may be opened up into the form of a tube of rectangular cross-section; the transverse partition elements or flaps at this time lying at the top and parallel with the bottom which is still in a flattened condition. After the carton has been opened as just described the bottom must be pressed up so as to be in the form of an inverted V in cross-section, and the transverse partitions must be swung down and interlocked with the bottom. It is the purpose of my improved machine to perform these last two functions.

The machine comprises a suitable frame 1 open at the top, the width of the frame being approximately equal to the width of the carton, and the length being somewhat greater than the length of the carton. What may be termed the rear wall or side 2 of the frame extends a considerable distance above the front wall or side 3. There is a stop 4 on the inner side of the rear wall near one end. The carton to be set up, after it has been opened, as heretofore explained, is laid on the frame, upside down, with the rear side wall of the carton resting against the rear wall of the frame, and one end of the carton engaged with the stop; the carton being thus accurately located with respect to the frame.

Mounted within the opening in the frame are a series of pairs of grippers so disposed that they may be operated to engage with the transverse partition elements of the carton and swing them into upright positions; the grippers of each pair lying on opposite sides of the corresponding partition element and clamping the latter between the same so as to hold it accurately in a predetermined vertical position, namely in a position such that the hooks thereon register with the corresponding slots in the bottom wall of the carton. Means are provided for then pressing down the bottom of the carton along the longitudinal center line, so as to force it into engagement with the hooks.

The grippers in the arrangement shown consist of a series of plates or wings 6 having shafts or trunnions 7 extending between 10 and at right angles to the front and rear walls of the frame, together with a second series of wings or plates 8 also provided with shafts or trunnions 9 extending between and at right angles to the front and rear sides 20 of the frame. The elements 6 may be simple flat plates radiating from their pivotal axis. In order to prevent interference between the element 8 of one pair of grippers and the element 6 of the next pair, the elements 8 are 30 bent so as to be L-shaped. Therefore the pivotal axis of each of the elements 8 may be displaced toward one side and below the pivotal axis of the cooperating gripping element. The parts are so disposed that each gripping 35 element 8 extends downwardly and laterally underneath the pivotal axis of the corresponding gripper element 6, and then upwardly past such pivotal axis on the far side of the latter. Normally, when the machine is not in use, 40 the plates 6 are all inclined in one direction and to the same extent, whereas the free arms or flanges of the elements 8 are inclined in the opposite directions. However, when the upper gripper elements are swung in the 45 clockwise direction, as viewed in Fig. 5, and the lower gripper elements are swung in the counterclockwise direction, the elements 6 may be brought into vertical positions with the free arms or flanges, or at least the ends 50 of the latter, lying parallel therewith as shown in Fig. 6.

The gripper elements being in the positions shown in Fig. 5 and the inverted opened carton being pressed down on the same, it will 55 be seen that the free ends of the transverse partitions or flaps E strike the gripper elements 6 and are partially swung up by the latter. When the carton is pressed down as far as it will go, it is brought to rest on the 60 top of a rail 10 at the rear of the frame and on top of the front wall or rail 3; one side of the carton being engaged with the rear wall or bar 2 and one end with the stop 4. If now the gripper elements are swung up 65 as heretofore explained, the elements 6 will

gradually swing the flaps or partitions in the carton into vertical positions, whereas the free ends of the gripper elements 8 will swing over and engage with the opposite sides of the flaps or partitions. The result is that the flaps or partitions will be positively held in vertical positions as indicated in Figs. 6, 8 and 10 namely in registration with the slots F in the bottom of the carton.

After the flaps have been swung up and are held in upright positions a long blade 12 may be pressed down along the longitudinal center of the bottom, forcing the bottom into a trough-shape as best shown in Fig. 9. As the bottom of the carton is depressed and deformed, the hooked ends e on the transverse partitions pass through the slots F, so that the free ends of the transverse partitions become interlocked with the bottom of the carton.

In order to permit the bottom of the carton to be pressed down into a trough shape, the central portions of the gripping plates are cut away at the top to form therein deep V-shaped notches 14, the open sides of which are almost as long as the width of the plates.

The grippers and the movable blade may be actuated in any suitable manner. In the arrangement shown, the shafts or trunnions for the gripper elements project at the rear side of the frame and the projecting end of each is provided with a radial arm fixed thereto. The arms connected with the upper shafts or trunnions 7 are indicated at 15 and those associated with the lower set of shafts or trunnions are indicated at 16. The arms 15 are all parallel with each other as are also the arms 16. The arms 15 are connected together by a suitable connecting rod 17, and a second connecting rod 18 extends between the free ends of the arm 16. The connecting rod 17 has an arm 19 extending downwardly from one end thereof past the rod 18. A pin 20 on the rod 18 projects into a vertical slot 21 in the arm 19. Consequently if one of the connecting rods is reciprocated in the direction of its length, the other will be given corresponding movements. One of the arms 7 is provided with an upward extension 22.

On the part 22 is a roller 23 that extends into a cam groove 24 in a cam block 25 on the rear side of the machine. The cam block is fixed on a horizontal shaft 26 extending parallel with the longitudinal axis of the machine on the rear side of the latter. The shaft 26 is supported in suitable brackets 27 projecting rearwardly from the frame, or otherwise. An operating lever or handle 28 is fixed to and extends radially from one end of the shaft 26. The shaft 26 has thereon two arms 29, 29, each lying in a plane at right angles to the longitudinal axis of the shaft, and being of U shape. The blade 12 extends between and is fixed to the outer ends of the arms 29.

The cam groove 24 has an initial diagonal section and a final section whose long axis is in a plane at right angles to the long axis of the shaft 26. When the machine is open as shown in Figs. 1, 4, 5 and 7, the cam roller lies in that end of the inclined section of the cam groove remote from the final or terminal section. Consequently when the operating lever or handle 28 is swung up, the first result will be the shifting of the connecting rods 17 and 18 toward the left as viewed in Fig. 1 and toward the right as viewed in Fig. 4. In other words, the partition raisers and grippers will be swung from the positions shown in Fig. 5 to those shown in Fig. 6. Then, when the cam roller enters the straight portion of the cam groove, no further movement of the connecting rods can take place but they and the gripper elements are locked against displacement and the transverse partitions are positively held in upright positions. However, the blade 12 is permitted to swing down as the cam roller travels through the straight portion of the cam groove, into the position illustrated in Fig. 9. In other words, normally the operating lever or handle is horizontal as shown in Fig. 7, so that the carton may be placed in position on the machine. Then, when the handle is swung up into about the position in Fig. 8, the transverse partitions have been raised and definitely positioned in registration with the slots F in the bottom of the carton. As the swinging movement of the handle continues, the blade 12 descends and presses the longitudinal center of the bottom of the carton down until the condition illustrated in Fig. 9 is reached. Then, when the handle is again swung back into the position illustrated in Fig. 7, not only is the blade 12 moved out of the way, but the grippers are again opened and the carton, fully set up, may be lifted from the machine; the machine being then ready to receive another carton.

Either or both of the gripping elements of each pair may be made more or less resilient so as to insure a firm grip on the transverse partitions of the carton. Because of the greater length of the bent gripper elements, there will ordinarily be enough resiliency in the latter to permit the cooperating gripper elements to be made comparatively stiff and thus insure the accurate positioning of the partitions when the grippers are closed.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:—

1. In a machine of the character described, a series of pairs of grippers, means for sup-

porting the grippers to permit those of each pair to move between a position in which they converge from the upper ends downwardly and a position in which they stand vertical in proximity to each other, and means for moving the grippers between said positions. 70

2. In a machine of the character described, a series of pairs of grippers, means for supporting the grippers to permit those of each pair to move between a position in which they converge from the upper ends downwardly and a position in which they stand vertical in proximity to each other, a blade long enough to extend across all of the grippers, and means for supporting the blade to permit it to be moved between an idle position and a position in proximity to and extending across all of the grippers. 75 80

3. In a machine of the character described, a frame open at the top, said frame having elements to support a carton inverted thereon and accurately position it lengthwise of the frame; a series of pairs of gripping jaws extending transversely across the frame and mounted thereon so as to be movable between positions in which the jaws of each pair stand close together and upright and positions in which the jaws are spread apart at the top, means for actuating the jaws, and means for pressing down along the longitudinal center line of a carton resting on the frame. 85 90 95

4. In a machine of the character described, a frame open at the top, said frame having elements to support a carton inverted thereon and accurately position it lengthwise of the frame; a series of pairs of gripping jaws extending transversely across the frame and mounted thereon so as to be movable between positions in which the jaws of each pair stand close together and upright and positions in which the jaws are spread apart at the top, a blade adapted to be pressed down along the longitudinal center of a carton resting on the frame, and means for moving the jaws into their closed positions and subsequently forcing the blade down toward the same. 100 105 110

5. In a machine of the character described, a frame open at the top, said frame having elements to support a carton inverted on the frame and accurately position the carton lengthwise of the frame, a series of pairs of gripping jaws mounted within the frame and distributed along the same, the jaws of each pair extending transversely of the frame, means for supporting the jaws so as to permit the jaws of each pair to swing from positions in which they stand upright in proximity to each other and positions in which the jaws are spread apart and converge toward each other from the upper ends downwardly, the middle portions of the jaws being cut away to produce deep V-shaped notches, means for moving the jaws between their opened and closed positions, and a blade adapted to be 115 120 125 130

pressed down along the longitudinal center of the bottom of an inverted carton to force it into said notches.

6. In a machine of the character described, a frame open at the top, devices arranged within the frame and distributed along the same to engage transverse partitions of a collapsed carton overlying the frame and set them in vertical positions, a blade long enough to extend across all of said devices, means for supporting the blade to permit it to be moved between an idle position and a position in proximity to said devices, and means for operating said devices and said blade.

7. In a machine of the character described, a frame open at the top and adapted to support a collapsed carton having transverse partitions adapted to project at their free ends into the space within the frame, and means within the frame for gripping said flaps and setting them in upright positions.

In testimony whereof, I sign this specification.

MARTIN BURGER.
